The invention relates to the construction of the cooling zone of tunnel kilns, and especially though not essentially to such kilns for firing ceramic and similar products.

In a known construction of the cooling zone of a tunnel kiln, cooling of the fired goods takes place simultaneously by radiation and convection to heat exchangers arranged in the kiln channel and traversed by a gaseous or liquid cooling medium. These heat exchangers are preferably arranged in chambers formed by ribs extending from the kiln arch transversely to the kiln channel and are adapted to be screened to a certain extent from the interior of the kiln channel for the purpose of regulating the cooling process.

This adjustable screening of the heat exchangers is accomplished in the known construction of cooling zones by pairs of plate-like dampers of fireproof material arranged below or ahead of the heat exchangers and lying in the kiln arch and/or the side walls of the kiln channel, and supported by the ribs forming the chambers or by lateral extensions thereof for movement towards and away from each other. These pairs of plate-like dampers leave a slit of variable width between their opposing edges, through which the kiln atmosphere comes into direct contact with the heat exchangers and through which the cooling depending on radiation also takes place.

In this manner, however, only a comparatively rough adjustment of the cooling curve is possible. This is particularly disadvantageous where the mass of goods being fired (and so its heat capacity) varies appreciably in the longitudinal direction of the train of firing bogies. This is, for example, particularly the case in the firing of earthenware pipes of different diameters, where the geometric variations of the fired masses to be cooled and the corresponding variation in quantity of heat to be dissipated can be as high as in the ratio 1.2, which has to be controlled by adjustment of the openings or the degree of screening of the cooling devices.

Another important difficulty, present not only in such extreme cases but also in normal ones, which arises from the fire adjustment of the effect of the heat exchangers required for satisfactory cooling of delicate ceramic goods is because the region within which direct connection takes place between the heat exchangers arranged in the kiln arch and the interior of the kiln channel always lies at the center of the arch. The slit formed between the inside edges of the dampers when suitably adjusted thus has a chimney-like draught effect on the kiln atmosphere which results in unfavourable current conditions. Admittedly this may be tolerated in those temperature ranges in which rapid cooling is not dangerous and local differences therefore do not play such a decisive part; but this is not so in temperature ranges in which the goods being fired are particularly sensitive, as, for example, temperatures in the vicinity of the quartz conversion point (575° C.).

A further disadvantage of the known adjustable screening of the heat exchangers from the interior of the kiln channel resides in the fact that the masses of the dampers (consisting of ceramic material) become so great as the width of the kiln channel increases, that their free move-

2

ment through small distances, as is required particularly for automatic control is no longer possible. This disadvantage is particularly serious because there is a desire to increase the width of tunnel kilns used in the ceramic industry as far as possible with a view to increasing their output; at present tunnel kilns are already being used with a working width of the tunnel channel of 13 feet or more.

An object of the present invention is to overcome the aforesaid disadvantages and limitations and to provide finely controllable and more or less far reaching screening of the heat exchangers from the kiln channel, in dependence on the variations in the amount of heat to be extracted from the goods to be cooled, either manually or, in particular, by automatic control of the operation of the screening device.

According to one aspect of the invention, this is achieved by subdividing the openings of variable size by which the kiln atmosphere gains access to the heat exchangers in the transverse chambers into a plurality of such openings which are arranged, in the transverse direction of the kiln channel, in equidistant succession, spaced by bridges of appropriate width and provided with suitably constructed screening devices slidably arranged in the plane defined by the upper surfaces of the bridges.

Through these openings, which are preferably disposed in lateral regions of the kiln channel, a communication controllable by the position of the dampers is provided between the interior of the kiln channel and the heat exchangers arranged above it at locations which are evenly distributed over the width of the kiln channel, thus eliminating the intensive chimney effect of a single opening provided at the centre of the kiln channel.

The arrangement and construction of these openings and of the dampers are preferably matched to the various conditions ruling in the various regions of the cooling zone.

In the region at the beginning of the cooling zone where only rough control is required, subdivision into only two openings usually suffices. The middle region of the arch is screened from the heat exchangers by a single, fixed, comparatively wide bridge, the openings being formed on either side thereof, and each being closable to a greater or lesser extent by an inwardly or outwardly movable damper of appreciably smaller weight.

The width of the openings and thus the size of the dampers is preferably substantially equal to the thickness of the side walls of the kiln channel, so that the dampers lie wholly within guide slits in the walls when in their fully retracted position, without protruding laterally from the kiln contour.

In the zone of the kiln channel in which the goods being fired traverse the dangerous range of temperatures, the openings are preferably further sub-divided, a plurality of damper members for the controllable closing of the openings being rigidly coupled by spacers of suitable construction, so that all the dampers can be moved simultaneously in one direction or the other by operating rods which are preferably provided on each side. This may be done from one side of the kiln channel.

In the case of a kiln channel of comparatively great width the damper members are conveniently pulled to and fro alternately from one side of the channel to the other.

The damper members too may be differently constructed for successive zones, according to the different temperature and insulation conditions to which they are subjected.

In the hotter zones they preferably consist of fireproof ceramic material, preferably of light weight, such as one of the known light weight refractories and, in the zones

of the lower temperature, of suitably temperature resistant sheet metal.

In the adjacent low temperature zones one-piece sheet metal dampers are preferably used which extend over the entire width of the kiln channel and which, in their basic construction, consist of a simple metal strip having rectangular openings suitably spaced apart by bridges. With a view to increasing the insulating effect of such a metal strip against the kiln atmosphere, the transverse bridges may, if desired, be covered with suitable insulating material which may be accommodated in grooves formed by sheet metal U-sections mounted on the dampers and simultaneously acting as stiffeners therefor.

Where an improvement in the insulating effect is required smaller than that obtainable from covering the sheet metal damper with ceramic insulating material it may suffice to form the dampers out of two or more relatively spaced layers of sheet metal.

The ceramic or sheet metal dampers are supported, in known manner, by mutually opposing lugs on the vertical ribs which separate the successive cooling zones in the longitudinal direction of the kiln.

According to a further feature of the invention, the position of the dampers is controlled automatically, this being by means of temperature sensing devices arranged in successive regions in the direction of advance of the firing bogies and adjusted to a predetermined temperature, whereby control impulses are generated upon departure from this predetermined temperature, to cause movement of these screening means in an opening or closing direction. Thereby the temperature gradients in the successive sub-zones which are individually regulated by the sensing devices, can be made greater in the regions of higher temperature and successively smaller in the regions of lower temperature; that is the temperature conditions are only roughly controlled in the first regions, but finely in the subsequent ones, the control being all the easier in the latter regions because very light and correspondingly easily movable screening devices are used therein.

The temperature sensing devices in the various regions can also simultaneously control the passage of the cooling medium through the heat exchanger in a manner known per se.

The application of the basic concept of the invention to heat exchangers arranged in the side walls of the kiln channel requires no special explanation.

The above and other features of the invention will be apparent from the following description of constructional examples thereof, with reference to the accompanying drawings, in which:

FIG. 1 is a vertical section through the top portion of a tunnel kiln with the known construction of adjustable screening of the heat exchanger.

FIG. 2 is a horizontal section on line A—B in FIG. 1 showing above the open and below the closed position of the dampers and

FIG. 3 is a section on line C—D of FIG. 2.

FIGS. 4 to 6 show one arrangement of screening devices according to the invention, the views corresponding to those of FIGS. 1 to 3,

FIGS. 7 to 9 show corresponding views of a second construction,

FIG. 10 is a plan view of a sheet metal damper,

FIG. 11 is a side view of FIG. 10,

FIGS. 12 and 13 show a further construction of a sheet metal damper, the views corresponding to FIGS. 10 and 11.

Referring to FIGS. 1 to 3 the kiln channel of a tunnel kiln in the region of the cooling zone comprises side walls *a'*, *a''* covered by an internal insulating layer *b'*, *b''* and a cover *c*.

A train of firing bogies, of which only the charge *d* on one bogie is shown, passes through the free kiln channel.

From the cover *c* extend vertical ribs *e* spaced at in-

tervals in the longitudinal direction of the kiln channel. These ribs are of inverted T-section and have lateral flanges *h'*, *h''*, heat exchangers *f* lie in the chamber-like spaces formed between the ribs *e* and are connected to outwardly extending feed and discharge conduits *g* for the cooling medium.

Damper members *i'*, *i''* rest on the lateral flanges *h'*, *h''* of the ribs *e* and comprise rectangular plates of ceramic material; they are slidable in the transverse direction of the kiln channel by means of rods *k'*, *k''* provided with handles and extending through openings in the side walls *a'*, *a''* of the kiln channels.

In the position according to the top portion of FIG. 2 the dampers completely close the openings formed between the mutually opposing lateral flanges *h* of adjacent ribs *e*, and in the position shown in the bottom portion of FIG. 2 they leave open a central opening *l* which is symmetrical about the longitudinal axis of the kiln channel. Through this opening the kiln atmosphere gains access to the spaces in which the heat exchangers *f* are disposed.

FIGS. 4 to 6 show the first embodiment of the invention, namely one particularly suitable for the starting region of the cooling zone in which the temperatures are still appreciably above the quartz conversion point and only rough temperature control is required.

In this embodiment, the opening between the supporting means or mutually opposed flanges *h'*, *h''* of two successive vertical dividing means or ribs *e* is bridged in the central region by a fixed bridge *m* lying on the flanges *h'*, *h''*. Dampers *n'*, *n''*, which also consist of ceramic material and which compared with those of FIGS. 1 to 3 are of considerably reduced width, are supported on the flanges *h'*, *h''* and can be slid up to the bridge *m*, in order fully to close the lower openings of the chambers containing the exchangers *f*, as shown in the top portion of FIG. 5. As shown in the lower portion of FIG. 5 they may be moved outwardly to leave these openings free.

In this manner, the kiln atmosphere can be brought into communication with the spaces containing the heat exchangers over a controllable range via the openings formed on either side of the central bridge *m*.

In the construction according to FIGS. 7 to 9, an even further sub-division takes place as compared with that of FIGS. 4 to 6, namely into three openings *o'*, *o''*, *o'''*, as shown. In this case the openings are formed by two transverse bridges *p'*, *p''*, which connect the mutually opposed flanges *h'*, *h''*. In this case four damper members *q'*, *q''*, *q'''*, *q''''* of somewhat greater width than the openings *o* are used. These are connected to each other, by pairs of rods *r'*, *r''* which also constitute spacers, at distances corresponding to the width of the openings *o*. The damper members are arranged to slide in one or other direction so as to close the openings either entirely or partially or to leave them fully open. The dampers are moved by means of the actuating rods *k'*, *k''* arranged on either side thereof.

In the extreme left hand position, the second damper member *q''* closes the opening *o'*, the following one *q'''* closes the opening *o''* and the following one *q''''* closes the opening *o'''*, while the damper member *q'* is out of action. In the extreme right hand position the sequence is reversed and the damper member *q''''* is out of action. FIG. 8 shows two possible positions of the damper members and of the controllable adjustments to the openings *o'* to *o'''*.

FIGS. 10 and 11 show a damper which is particularly suitable for the zones of low temperature. It comprises a rectangular sheet metal plate *t*, provided with openings *s'*, *s''*, *s'''* and with actuating handles *k'*, *k''* attached to the plate. FIGS. 12 and 13 show corresponding views of a different construction of such a sheet metal damper, in which U-shaped sheet metal troughs are welded to the transverse bridges separating the openings *s* of a like base

plate t , the troughs being filled with insulating material v .

The possible automatic control of the damper arrangement shown in accordance with the temperature conditions, by means of a temperature sensing device associated with each damper, is not shown in the drawings.

Obviously the invention is not confined to the constructions hereinbefore described in detail and illustrated in the drawings; numerous modifications thereof are possible without departing from its basic concept.

We claim:

1. A tunnel kiln having a cooling zone, a plurality of ribs in spaced longitudinal relation along said zone, said ribs providing a plurality of chambers, a heat exchanger in each of said chambers, at least one bridge member extending between the ribs defining each chamber to provide openings on each side of said bridge member in communication with the interior of said kiln and dampers for each of said openings movable to controllably screen said heat exchanger from the interior of said kiln.

2. A tunnel kiln comprising side walls, and an arch defining a cooling zone, transverse ribs spaced along the length of said zone and depending from said arch, said ribs defining a plurality of chambers, a heat exchanger in each of said chambers, a wide bridge member extending between each pair of ribs along the centre line of said arch and defining with said side walls an opening on each side of said bridge connecting said chamber with the interior of said kiln, and dampers slideable across each of said openings to a controllable extent to screen said exchanger from the interior of said kiln.

3. A tunnel kiln comprising side walls, and an arch defining a cooling zone, transverse ribs spaced along the length of said zone and depending from said arch, said ribs defining a plurality of chambers and having lower flanges extending horizontally, a heat exchanger in each of said chambers, a wide bridge member extending between each pair of ribs along the center line of said arch and defining with said side walls an opening on each side of said bridge connecting said chamber with the interior of said kiln and dampers supported on the horizontal flanges of said ribs and slideable across each of said openings to a controllable extent to screen said exchanger from the interior of said kiln, said bridge lying above the plane of said horizontal flanges with its side edges constituting stops limiting the sliding movement of the dampers.

4. A tunnel kiln comprising side walls, and an arch defining a cooling zone, transverse ribs spaced along the length of said zone and depending from said arch, said ribs defining a plurality of chambers, a heat exchanger in each of said chambers, a plurality of bridge members extending parallel to one another between each pair of ribs and defining a plurality of openings connecting said chamber with the interior of said kiln, and dampers slideable across each of said openings to a controllable extent to screen said exchanger from the interior of said kiln.

5. A tunnel kiln comprising side walls, and an arch defining a cooling zone, transverse ribs spaced along the length of said zone and depending from said arch, said ribs defining a plurality of chambers, a heat exchanger in each of said chambers, a plurality of bridge members extending parallel to one another between each pair of ribs and defining a plurality of openings connecting said chamber with the interior of said kiln, a plurality of dampers greater by one than the number of said openings and each of slightly greater width than the associated opening, rigid spacers connecting said dampers and means for moving said dampers simultaneously in a plane defined by the upper surfaces of said bridges.

10 6. A tunnel kiln as defined in claim 5 wherein said dampers are formed by a rectangular sheet metal plate having a plurality of openings therein.

15 7. A tunnel kiln as defined in claim 5 wherein said dampers are formed by a rectangular sheet metal plate having a plurality of openings therein, channel members affixed to the plate between the openings and heat insulating material within said channel members.

20 8. A tunnel kiln comprising side walls, and an arch defining a cooling zone, transverse ribs spaced along the length of said zone and depending from said arch, said ribs defining a plurality of chambers, a heat exchanger in each of said chambers, a plurality of bridge members extending parallel to one another between each pair of ribs and defining a plurality of openings connecting said chamber with the interior of said kiln, a plurality of dampers greater by one than the number of said openings and each of slightly greater width than the associated opening, rigid spacers connecting said dampers and means for moving said dampers simultaneously in a plane defined by the upper surface of said bridges.

25 9. A tunnel kiln having a cooling zone a plurality of dividing means defining chambers adjacent the cooling zone, at least one bridge member extending between adjacent dividing members defining each chamber to provide openings on each side of said bridge member, each of said chambers communicating with the interior of the kiln through at least two openings, a heat exchanger in each of said chambers, means for passing cooling fluid through said exchangers, supporting means carried by said dividing means, and obturating means for each of said openings supported by said supporting means, said obturating means controllably adjustable to screen said heat exchanger from the interior of said kiln.

30 10. A tunnel kiln as defined in claim 9 including temperature sensing devices within the kiln tunnel, each device being associated with said obturating means, and means controlled by said temperature sensing devices to move said obturating means across said openings.
